DESIGN FOR A LADY'S HANDBAG OR SIMILAR ARTICLE

George W. Headley, 3d, New York, N. Y., assignor to Paul E. Flato, New York, N. Y.

Application October 4, 1938, Serial No. 80,241

Term of patent 3½ years

To all whom it may concern:

Be it known that George W. Headley, 3d, a citizen of the United States and resident of New York city, in the county of New York and State of New York, has invented a new, original, and ornamental Design for a Lady's Handbag or Similar Article, of which the following is a specification, reference being had to the accompanying drawing, forming part thereof, in which the figure is a perspective view of a lady's handbag or similar article, embodying my new design.

The rear and front end of the handbag are substantially like the front and end shown, except for the omission of the flap member.

The design is characterized by the cord-like members disposed as shown on the outer surfaces of the handbag, the portions of said cord members contacting said surfaces being permanently attached thereto together with the free loops extending from the top surface of the handbag as shown.

I claim:

The ornamental design for a lady's handbag or similar article, substantially as shown and described.

GEORGE W. HEADLEY, 3RD.
